UNITED STATES PATENT OFFICE.

ROBERT T. POLLOCK, OF BROOKLINE, MASSACHUSETTS, ASSIGNOR TO UNIVERSAL OIL PRODUCTS COMPANY, OF CHICAGO, ILLINOIS, A CORPORATION OF SOUTH DAKOTA.

APPARATUS FOR TREATING OILS.

Application filed June 25, 1924. Serial No. 722,897.

To whom it may concern:

Be it known that I, ROBERT T. POLLOCK, a citizen of the United States, residing at Brookline, in the county of Suffolk and 5 State of Massachusetts, have invented certain new and useful Improvements in Apparatus for Treating Oils, of which the following is a specification.

This invention relates to an apparatus 10 for treating oils and refers more particularly to an apparatus employed in a continuous process for cracking hydrocarbon oils to produce light hydrocarbons such as gasoline or the like. This application constitutes a continuation in part of my application 15 No. 411,913, filed September 22nd, 1920.

Among the salient objects of the invention is the provision of an improved conversion 20 chamber adapted to receive oil and vapors from a heating zone and in which chamber carbon is collected, and one especially adapted for use in the cracking of heavy oil in which there is an excessive deposit of carbon 25 in the reacting chamber.

More particularly it is an object of the present invention to overcome difficulties encountered by the formation of coke in the reacting chamber in continuous cracking 30 processes, by the provision of a vertical reacting chamber provided with carbon discharge means and with a plurality of vertically disposed residuum draw-off means.

In the drawing, the figure represents a 35 side elevation partly in section showing diagrammatically a still equipped with a vertical reacting chamber illustrating my invention.

In the treating of hydrocarbon oils and 40 particularly heavier oils such as Mexican and Californian gas oil, provision must be made for the accumulation of carbon deposits in the vapor or reacting zone during the cracking of the oil. As much as seven 45 or eight times the amount of carbon is deposited in the vapor zone in the cracking of Californian and Mexican oils as there is in mid-continent oils. To provide an apparatus which will accommodate this excessive 50 accumulation of carbon and at the same time obviate the necessity of shutting down the plant at frequent intervals for cleaning, I have incorporated a number of features into the apparatus here explained to meet these 55 difficulties.

In carrying out the process of cracking oils, the constancy of the temperature is exceedingly important as it very materially affects the quantity and character of the yield of distillate produced. I have found that 60 by employing a vertical reacting chamber provided with vertically spaced residuum draw-off lines, it is possible to keep a substantially constant depth of liquid oil in the reacting chamber for desired periods while 65 this liquid oil is still undergoing cracking to maintain a uniform flow of vapors from the reacting chamber to the dephlegmator of a substantially uniform quality, thereby securing a substantially constant temperature 70 control which cannot be readily secured when a horizontal reacting chamber is employed.

Referring to the drawing, the raw oil is introduced from any conventional source, 75 not shown, to the inlet pipe 1 into the top of the dephlegmator 2 where it passes down in an opposed direction to the travel of the oil vapors and collects in the lower leg 3 of the dephlegmator 2 and is directed therefrom by pipe 4 to the cracking tubes 5. The cracking or heating tubes 5 are mounted in the furnace 6 which is preferably heated by means of gas burners 7. The oil, after being heated in the cracking tubes, passes 80 through line 8, in which is placed a suitable throttle valve 9, to the vapor tank or reaction chamber 10.

In describing in detail the construction 90 of the reacting chamber, it will be noted that the chamber is cylindrical in form having a rounded top and bottom provided with large cleaning openings as shown at 11 and 12. The lower cleaning opening 12 is provided with a pivoted door 13 which may be 95 swung down so that easy access can be had to the interior of the tank for cleaning. A residuum draw-off line 14 communicates with the lower portion of the chamber and is controlled by suitable throttle valve 15 by 100 means of which the heavy residuum and suspended carbon may be drawn off as the apparatus is being brought on stream. The reacting chamber is further provided with a plurality of vertically spaced residuum draw-off lines 16, 17 and 18 provided with 105 throttle valves 19, 20 and 21 respectively. As the length of a run increases the carbon accumulates in solid coke-like masses in the reacting chamber and the residuum draw-off 110

line 16 will gradually become coked over by the deposits of carbon. When this occurs the next higher draw-off line may be brought into service and the liquid depth in the reacting chamber can thus be maintained substantially constant. By positioning the residuum draw-off lines in this manner practically the entire reacting chamber may be filled with carbon before necessitating cleaning thereof. Also this vertical construction of the cylindrical reacting chamber and the uniform spacing of the residuum draw-off lines results in the maintaining of a constant surface area of the liquid in the chamber as well as a constant depth of liquid therein as the chamber is being progressively filled by the deposit of carbon. These features materially aid in maintaining a constant temperature and uniform run even after the vaporizing chamber has become largely charged with coke, inasmuch as the coke deposits have no effect on the quantity, surface area or depth of the liquid oil always present in the chamber and undergoing conversion. The large diameter of the reacting chamber facilitates the cleaning thereof as distinguished from the long, narrow tubes lying horizontally.

The reacting chamber or tank is mounted within a heavily insulated enclosure 22. Fire brick, kieselguhr or other heat insulation may be used. From the top of the reacting chamber or tank a vapor line 23 controlled by valve 24 connects the reacting chamber to the dephlegmator 2. The vapor line is so arranged that any condensate forming therein will flow into the dephlegmator and there combine with the raw oil to be re-treated in the cracking tubes. The oil vapors which are released in the reacting chamber and rise to the vapor line 23 are dephlegmated in the aerial dephlegmator 2 by the incoming raw oil and the lighter fractions thereof pass from the dephlegmator 2 through vapor line 25 to the usual condenser 26 from which the distillate passes through line 27 to a conventional receiver 28 provided with draw-off 29 controlled by throttle valve 30 and also provided with an uncondensable gas outlet 31 controlled by valve 32. The valves 30 and 32 are also employed to regulate the pressure on the entire apparatus which may be maintained at substantially 100 pounds per square inch.

In operation, the oil after passing through the cracking tubes is at an approximate temperature of 850 degrees F. and is introduced to the vertically disposed reacting chamber

wherein the light oils vaporize and the heavier residuum and carbon are deposited, 60 the vapors passing on to the dephlegmator 2, thence through the condenser and to the receiver as distillate. As the carbon deposits build up in the reacting chamber and coke over each successive residuum draw-off, the 65 next higher residuum draw-off is brought into use and in this way the depth of liquid residuum in the reacting chamber is maintained substantially constant, thereby lending uniformity to the cracking operation 70 both as to the product and the yield while the chamber is being gradually filled with carbon.

I claim as my invention:—

1. In an apparatus for converting oil, the 75 combination with a furnace, of a continuous heating coil disposed therein through which oil is passed to be subjected to a cracking temperature, of an enlarged vertically disposed insulated expansion chamber located 80 outside of said furnace, means for introducing the heated products of conversion from said heating coil to be discharged into the upper portion of said expansion chamber, a 85 vapor discharge line leading from said expansion chamber near its upper end, a plurality of independently controlled residual draw-off lines leading from said expansion chamber at different vertical positions, independent means for controlling each draw-off 90 line, and a carbon discharge in the bottom of said chamber, and means for controlling the discharge of carbon therefrom.

2. In an apparatus for treating hydrocarbon oils, the combination with a furnace, of 95 a continuous elongated cracking coil disposed within said furnace, means for feeding oil to said coil to be subjected to a cracking heat, an enlarged vertically disposed tubular expansion chamber adjacent said furnace, an insulating jacket around said chamber, means for discharging heated oil from said cracking coil into said expansion chamber near the upper end thereof, a vapor discharge line from said chamber, a series of 100 vertically spaced residual draw-off lines leading from said chamber at different vertical points, independent controlling valves in each of said lines whereby the residuum may be withdrawn from said chamber at different vertical positions as carbon accumulates 105 therein, said chamber having near its lower end a carbon discharge, and means for opening and closing said carbon discharge.

In testimony whereof I affix my signature.
ROBERT T. POLLOCK.
